UNITED STATES PATENT OFFICE.

ABRAHAM H. BOYD, OF ASPINWALL, PENNSYLVANIA, ASSIGNOR TO THE PORTER RUBBER COMPANY, OF SALEM, OHIO, A CORPORATION OF OHIO.

DESIGN FOR A VEHICLE-TIRE.

49,535.

Specification for Design.

Patented Aug. 22, 1916.

Application filed May 27, 1916. Serial No. 100,400. Term of patent 3½ years.

To all whom it may concern:

Be it known that I, ABRAHAM H. BOYD, a citizen of the United States, residing at Aspinwall, in the county of Allegheny and State of Pennsylvania, have invented a new, original, and ornamental Design for a Vehicle-Tire, of which the following is a specification, reference being had to the accompanying drawing, forming part thereof.

In the drawings: Figure 1 is a plan view

of a portion of a vehicle tire, showing my new design. Fig. 2 is a cross sectional view taken on the line 2—2 of Fig. 1.

I claim:

The ornamental design for a vehicle tire, substantially as shown.

ABRAHAM H. BOYD.
